UNITED STATES PATENT OFFICE

2,519,699

RAPID CALCULATOR FOR USE WITH
CARPENTER'S SQUARE

Walter A. Peterson, King, Wis.

Application February 6, 1948, Serial No. 6,688

2 Claims. (Cl. 33—102)

1

This invention relates to a device of extremely simple construction adapted to be used with a conventional carpenter's square by carpenters, painters, plasterers, lumbermen, millwrights, plumbers and other tradesmen for solving numerous mathematical problems arising in connection with their work and which will enable such problems to be solved much more rapidly than by resorting to conventional mathematical methods.

A further object of the invention is to provide a device for the aforescribed purposes of extremely simple construction which is capable of being economically manufactured and sold and which will be extremely efficient and practical for its intended purposes.

A further object of the invention is to provide a device which may be employed by tradesmen generally and without requiring special skill in the use thereof in combination with a carpenter's square.

Another object of the invention is to provide a device for the aforescribed purposes and which may be utilized for solving many of the problems for which a slide rule is usually employed thereby, when utilized in conjunction with a carpenter's square, affording a rapid calculator for use by persons not familiar with the operation of a slide rule.

Various other objects and advantages of the invention will hereinafter become more fully apparent from the following description of the drawings, illustrating a presently preferred embodiment thereof, and wherein:

Figure 1 is a top plan view of the rapid calculator for use with a conventional carpenter's square;

Figure 2 is a longitudinal sectional view thereof taken substantially along a plane as indicated by the line 2—2 of Figure 1;

Figure 3 is a plan view showing the rapid calculator in a folded, inoperative position; and,

Figures 4 and 5 are plan views showing the rapid calculator in use with a conventional carpenter's square.

Referring more specifically to the drawings, the novel rapid calculator attachment for use with a carpenter's square and which is designated generally 7 includes a body, designated generally 8 which is preferably formed of a relatively thick, lightweight metal and which is provided with a straight edge 9. The body 8 is provided with an opposite edge 10 which converges in one direction toward the straight edge 9 to combine therewith to form the restricted

2

end 11 of the body 8 and which merges at its opposite end with a curved edge 12 forming the enlarged end 13 of said body 8. The body 8 is divided transversely into the end sections 11 and 13 along the line 14 and said sections are pivotally connected together by hinges 15, only one of which is illustrated, which are attached to the underside of the body 8 and by means of which the section 11 can be readily folded under the section 13 and so that the body 8 will assume the appearance as seen in Figure 3. It will also be readily apparent that when the sections 11 and 13 are extended, as seen in Figures 1 and 2, their adjacent edges will abut so that said sections will be disposed in the same plane. The body 8 is provided with depending foot members 16 adapted to engage a supporting surface for supporting the calculator 7 thereon and with the body 8 elevated sufficiently so that the hinges 15 will be out of contact with said surface, not shown.

A bar or fence 17 is disposed on the upper surface of the body section 13 and is provided with an elongated, longitudinally disposed opening 18 through which the shank of a fastening 19 loosely extends. The shank of the fastening 19 is threaded to engage a threaded upwardly opening recess 20 in the section 13 and is provided with a wing-shaped head by means of which said fastening may be readily advanced for clamping the bar 17 against the upper surface of the body section 13 or loosened to permit the bar 17 to pivot and slide on the fastening 19. The bar 17 is of a length substantially equal to the width of the body 8 at its widest point and is provided with a straight longitudinal edge 21 which, when disposed at a right angle to the edge 9 will extend from said edge to the opposite edge of the body 8 when said bar is clamped relatively to the body. With the bar 17 thus disposed and as illustrated in Figure 1, it will be noted that the upper surface of said body is provided with a plurality of lines which radiate from the meeting point of the edges 9 and 21 and with each of which is associated indicia describing miters of different degrees. These lines and the associated indicia, designated generally 22 may be suitably inscribed in the upper surface of the body 8.

The rapid calculator 7, previously described, is intended and adapted to be used in conjunction with a conventional carpenter's square as seen at 23 in Figures 4 and 5 including a blade 24 which is twenty-four inches in length and a tongue 25 which is sixteen inches in length as is

conventional. The tongue and blade are inscribed along their outer edges with linear measures, illustrated in inches but commonly including fractions of an inch up to one-sixteenth inch.

Numerous mathematical problems commonly occurring in construction work and in other operations performed by tradesmen may be quickly and easily solved with the calculator 7 and carpenters' square 23, one of which is illustrated in Figures 4 and 5 and wherein, for example, it is desired to ascertain the circumference of a circle, cylinder or tank which is six inches or feet in diameter. This result can be accomplished mathematically by multiplying the figure 6 by 3.1416 or by 22 and dividing by 7 to obtain a result which is sufficiently close. However, by positioning the carpenter's square 23 on the upper surface of the body 8 as illustrated in Figure 4 and with the fence or bar 17 loosened and with the outer edge of the tongue 25 engaging against the bar edge 21, the carpenter's square 23 is adjusted until the straight edge 9 intersects with the graduation "7" of the tongue 25 and the graduation "22" of the blade 24 and with the square 23 thus disposed, as seen in Figure 4, the fastening 19 is tightened for clamping the bar 17 at this angle. Since the diameter of the tank, cylinder or circle is six, the square 23 is moved until the graduation "6" of the tongue 25 intersects with the line 9, as seen in Figure 5 and the result or circumference can then be read at the intersection point of the outer edge of the blade 24 with said line 9 and will read 18 and $\frac{1}{2}$ inches. This position of the bar 17 may likewise be utilized for obtaining the diameter or circumference of any circle and it will be readily apparent that to obtain the diameter from the circumference the procedure is reversed and the blade 24 is adjusted so that the figure thereon representing the circumference intersects with the straight edge 9 and when thus positioned and with the tongue against the bar edge 21, the diameter will be indicated by the point of intersection of the outer edge of the tongue 25 with said edge 9.

To find the number of square yards in a wall, for example, one fourteen feet wide and ten feet high, the figure 9 is employed on the tongue of the square 23 instead of the figure 7 since there are nine square feet to a square yard and the figure 14, the length of the wall is employed in lieu of the figure 22 on the blade 24 and the fence or bar 17 is then set as previously described. As the height of the wall is ten feet the square 23 is moved until the graduation "10" of the tongue 25 intersects the straight edge 9 and the result can then be read on the point of intersection of the outer edge of the blade 24 with the straight edge 9.

Assuming that a pulley twenty inches in diameter driving a smaller pulley by a belt connection has a speed of 13 revolutions per second and that it is desired to decrease this speed to 11 revolutions per second, the square 23 is placed on the calculator 7 as previously described and as illustrated in Figure 4 and with the graduation "13" of the tongue intersecting the edge 9 and the graduation "20," representing the diameter of the drive pulley being used and indicated by said graduation of the blade 24 intersecting the edge 9. With the bar 17 thus angularly adjusted and clamped by the fastening 19, the square 23 is then moved until the graduation "11" of the tongue is on the straight edge 9 to indicate the desired number of revolutions and when thus disposed, the outer edge of the blade 24 will intersect the

straight edge 9 at its graduation representing 16 and $\frac{1}{2}$ inches and which is the diameter of the drive pulley required.

For solving problems in square root the figures "8½" and "12" are preferably used because the diagonal of a right angle two sides of which are each 8½ inches or feet is 12 inches or feet, respectively and because these are constant figures most frequently used in carpentry since 12 represents the run of a rafter. Accordingly, to find the diagonal or square root of the sum of the two equal sides of a right angle the square 23 is placed as in Figure 4 but with the "8½" inch graduation on the tongue intersecting the line 9 and the "12" inch graduation on the blade intersecting said line, after which the fence or bar 17 is clamped. By then adjusting the square 23 so that the figure on the tongue 25 will correspond to the length of one side of the right angle, the hypotenuse or square root of the sum of the two right angular sides thereof can be readily ascertained by reading the figure on the blade 24 at its intersection point with the edge 9.

The radial lines of the indicia 22 are utilized to obtain the cut for different miters and in employing the calculator 7 for this purpose, the fence or bar 17 is set as seen in Figure 1 at a right angle to the straight edge 9. It will be noted as seen in Figure 1, that the upper surface of the body 8 is inscribed with a line 26 which is disposed at right angles to the edge 9 and which meets said edge at the meeting point of the arcuate line of the indicia 22 with said edge 9. With the bar 17 set as seen in Figure 1, if it is desired to obtain a hexagon miter the square 23 is placed on the upper surface of the body 8 with the outer edge of the tongue 25 against the fence edge 21 and moved thereon until the graduation "12" of the blade 24 is at the intersection of the radial hexagon miter line of the indicia 22. When thus disposed the graduation "7" of the tongue 25 will align with the edge 9. By then placing the square 23 on the stock or object to be cut with the twelve inch graduation of the blade 24 and the seven inch graduation of the tongue 25 intersecting corresponding edges of said object, by cutting the object along the outer edge of the tongue 25 as thus disposed, the desired miter will be obtained. By placing the square 23 in the same manner but with the graduation "6" of the blade 24 on the pentagon line of the indicia 22, the "4½" inch line of the tongue will align with the edge 9 and by then applying the square, as previously described, to the stock or object, using the six inch mark on the blade and the four and a half inch mark on the tongue, the correct miter can be cut as previously described.

As previously stated, numerous other problems may be readily solved with the calculator 7 and carpenters' square 23 as only a few illustrated problems have been herein described and various modifications and changes in the structure of the calculator 7 are likewise contemplated and may obviously be resorted to, without departing from the spirit or scope of the invention as hereinafter defined by the appended claims.

I claim as my invention:

1. A rapid calculator attachment for use with a carpenter's square comprising a base having a substantially flat top surface and provided with a straight edge, a bar disposed on the top surface of the base, said bar having an elongated longitudinally extending slot intermediate of its ends, a thumbscrew extending loosely through the slot and adjustably anchored in the base, said thumb-

screw having a head disposed above the bar, said bar having a straight edge extending longitudinally thereof for cooperation with the straight edge of the base and adapted to be slidably engaged by the outer edge of the tongue of a carpenter's square and to be angularly adjusted with respect to the straight edge of the base by the disposition of the tongue and blade of the carpenter's square relatively to said straight edge of the base, the straight edge of the base being longer than either the blade or tongue of the square.

2. A rapid calculator as in claim 1, the upper surface of said base being inscribed with miter indicia including lines radiating from the apex of the straight edge of the base and the straight

edge of said bar when said straight edges intersect at a right angle.
